Term of patent 14 years

(Cl. D40—1)

FIG. 1

FIG. 2

FIG. 3

FIG. 1 is a rear perspective view of a hedge trimmer embodying my new design;

FIG. 2 is a side elevation as seen from the opposite side of FIG. 1;

FIG. 3 is a top plan view thereof;

FIG. 4 is a front elevation thereof;

FIG. 5 is a rear elevation thereof;

FIG. 6 is a rear perspective of a modified embodiment of the hedge trimmer shown in FIG. 1; and

FIG. 7 is a side elevation as seen from the opposite side of FIG. 6.

The dominant features of my design reside in the portions shown in full lines.

The handle has been omitted in FIGS. 3 and 4 and the cutting blade member is fragmentarily shown in FIGS. 2, 3 and 7 and omitted in FIG. 4, for convenience of illustration only.

We claim:

The ornamental design for a hedge trimmer, as shown and described.
